UNITED STATES PATENT OFFICE.

TACITUS WILLIAM GAILLARD, OF BROOKLYN, NEW YORK.

TOOL.

1,123,513.

Specification of Letters Patent.

Patented Jan. 5, 1915.

Application filed October 30, 1913. Serial No. 798,265.

To all whom it may concern:

Be it known that I, TACITUS WILLIAM GAILLARD, a citizen of the United States, and a resident of Brooklyn, in the county of Kings and State of New York, have invented certain new and useful Improvements in Tools, of which the following is a specification.

My invention relates to a tool capable of various uses, among them pulling off gears, wheels and bushings from shafts, forcing the same into position, bending or straightening metal articles of various kinds, serving as an arbor press and acting as a backstop for a ratchet drill. It has special utility in connection with the repair of automobiles, its wide range of adaptability suiting it particularly for such work. Tools of this general type in which are provided a cross-head, a spindle adjustable endwise therethrough and a plurality of rods mounted in said cross-head, the rods and the spindle working against each other, are familiar in the art, but my tool represents various notable improvements, some of which will now be enumerated. The spindle in my machine is not only mounted for endwise adjustment but is movable endwise in said cross-head independently of said adjustment, such movement being against a spring in one direction and with it in the other, the object of this arrangement being to enable the user of the tool to jar tight fitting parts loose by striking the upper end of the spindle and to do this without injuring the thread of the spindle. In the embodiment of the invention illustrated, the spindle is adjustably mounted in a nut held against rotation but movable toward the work against a yielding resistance furnished by a spring.

Another feature of my invention is the self-adjustability of the rods toward and from the spindle and also in other directions which enables them to take up whatever position is required for the most effective performance of the work in hand, the rods being mounted in blocks which are movable toward and from said spindle but in any normal position of use are supported against strain in the direction of the length of the rods. Frictional means, as shown, a spring or springs, is provided for yieldingly retaining the blocks in place. These blocks preferably take the form of trunnions and serve as universal joints between the rods and the cross-head. The tool is furthermore capable

of use with a suitably supported bed plate as an arbor press, or without said plate and with suitable terminals on the rods for pulling off gears, for bending, straightening, etc. It also has other advantages of construction to be hereinafter mentioned.

Referring to the drawings: Figure 1 is a perspective view of the tool without the bed plate and its supporting means. Fig. 2 is a vertical section on a plane passing through the long axis of the cross-head. Fig. 2^a is an inverted perspective view illustrating the manner in which the spindle is mounted. Fig. 3 is a detail view showing in section on the line 3-3, Fig. 2, the manner in which the rods are mounted in the cross-head. Fig. 4 is a detail perspective view illustrating one of the trunnion blocks and its springs. Fig. 5 is a perspective view of the tool provided with a bed plate duly supported. Fig. 6 is a detail view showing the end of a rod and its terminal in the form of a claw in which is secured a holding chain for use in bending, and Fig. 7 is a detail view of another form of terminal applied to a rod.

Referring more particularly to Figs. 1-4, my tool is provided with a cross-head 1 having a central body portion 2 and slots 3 extending outward therefrom in the direction of the length of the head, the said slots being provided with upper ledges 4 and lower ledges 4' to be hereinafter referred to. For convenience in carrying the tool and holding it up to its work, a handle 5 is secured to the cross-head. The body 2 is provided with a cavity 6 in which is movably mounted a block which I have illustrated as a nut 7 through which is screw threaded the spindle 8 which is thus adjustable endwise through the nut and cross-head. I give to the nut and the cavity in which it is located such shape as will prevent the rotation of the nut. In the drawings, I have shown the nut as hexagonal. The lower end of the cavity 6 is preferably provided with a closure or bushing 9 which may be screwed into the end of the body 2 to close the cavity and whose inner end forms an abutment 10 against which re-acts the spiral spring 11, the other end of which abuts against the under side of the nut 7. It will be apparent with the construction just described that the spindle 8 may be adjusted endwise by rotation with reference to the nut 7 and that it may move endwise with the said nut against the spring, any danger of stripping of the

threads being avoided. The spindle is provided with a head 12 to enable it to be rotated and above the same with a heavy removable cap 13 provided with relatively yielding material 14, as fiber, for contact with the end of the spindle, the purpose of this cap being to prevent the end of the spindle from being upset. The other end of the spindle is provided with a removable terminal 15 which may take any one of several forms and is preferably provided with relatively yielding material as fiber, as indicated at 16, in contact with the end of the spindle.

At each side of the spindle 8 and body 2 are mounted rods 17 which are freely movable endwise through blocks 18 and whose effective length is adjusted and maintained by the nuts 19, 20 located respectively above and below the said blocks. These rods whose function is ordinarily to exert a pull are provided with removable terminals 21 which may be of any of the forms shown or of other desired character. It will be understood that in the use of the tool the terminal 15 on the spindle 8 presses against one part of the work as, for instance, the end of a shaft and that the terminals 21 are in contact with other parts of the work as, for instance, the under side of the wheel or gear to be removed from the shaft. The turning of the spindle would thus result in the removal of the wheel or gear from the shaft and if the parts were a very tight fit, they might be jarred loose by striking the cap on the end of the spindle, the spring 11 permitting the spindle to move with its nut. Where the work might otherwise be marred, the terminals may be provided with comparatively soft material as fiber in the manner indicated at 22, Fig. 1.

It is obviously important that the rods 17 should be readily adjustable and I have arranged them so that they may take up any position within the total range of adjustment and that they may do this automatically to accommodate work of different sizes and in accordance with the strain on the rods, the rods thus finding their best position without the necessity of manual adjustment by the user of the tool. The construction which makes this possible is illustrated clearly in Figs. 3 and 4, the blocks 18 acting as there shown as trunnions extending across the slots 3 of the cross-head and having in their ends cavities 23 in which are located spiral springs 24, the outer ends of which are in contact with opposite faces 25 within the cross-head between the ledges 4 and 4'. This arrangement causes sufficient friction on said faces so as to hold the trunnion blocks yieldingly in place at any point in the slot 3 and the trunnions permit each rod to turn around the axis of its trunnion. Furthermore, sufficient play is permitted be-

tween the ends of the trunnions and the faces 25 and between the springs 24 and the cavities 23 in the ends of the trunnions so that the rods may also turn in any other plane, the result being an effective universal joint. In the construction shown, the movement of the rods is limited by the width of the slots but is quite sufficient for the purpose intended. The fact that the rods 17 may be adjusted without turning by merely manipulating the nuts 19, 20 makes quick adjustment possible and the arrangement of the trunnion blocks and related parts insures the correct location of the rods automatically in accordance with the requirements of the work in any given case.

In Fig. 5 the tool takes the form of a machine having the bed plate 26 supported by the rods or legs 27 which may be secured to the floor by feet 28. The rods 17 are screwed into the bed plate 26 when the tool is used in this way, the terminals 21 having been removed for the purpose. The tool may then be used as an arbor press.

Three different forms of terminals 21 for the rods 17 are illustrated, the form shown in Fig. 1 being as already stated, provided with the strip of fiber 22 to protect the work, the form shown in Fig. 6 being in the nature of the double claw 21^a to retain the chain 29 in place as, for instance, when tubing or rods are to be bent or straightened and the form shown in Fig. 7 which takes the shape of a foot 21^b provided with concentric corrugations for co-action with the work.

In order to permit the insertion and removal of the blocks 18 and their springs 24 an opening is made at the inner ends of the upper ledges 4 adjacent the body 2 so that the slots 3 are T-shaped at the top, the head of the T being wide enough for the purpose suggested. It may also be noted that the bottoms of the cavities 23 are inclined or beveled to facilitate movement between the blocks and the springs, the effect being on the order of a ball and socket joint. The bottoms of the said cavities may be curved.

What I claim as my invention is:

1. In a tool of the character described, a cross-head, a block yieldingly mounted thereon, and a spindle adjustable endwise in said block and also movable endwise with said block.

2. In a tool of the character described, a cross-head, a non-rotatable block movably mounted thereon, spring means opposing motion of said block in one direction, and a spindle adjustable endwise in said block.

3. A tool of the character described, comprising in combination, a cross-head, a spindle adjustable endwise in said cross-head, and resilient means for supporting said spindle yieldingly to permit endwise movement of said spindle independently of said adjustment.

4. In a tool of the character described, a cross-head, a block movable therein, a spring yieldingly supporting said block against movement toward the work, and a spindle screw-threaded in said block. 70
5. In a tool of the character described, a cross-head; a nut held against rotation with reference to the cross-head but movable endwise, a spindle screw-threaded in said nut, and spring means supporting said nut. 75
6. In a tool of the character described, a cross-head having a cavity therein, a nut in said cavity, means for preventing the rotation of said nut, an abutment on the cross-head adjacent said cavity, spring means acting between said abutment and nut to resist movement of the nut in one direction, and a spindle passing freely through said cross-head and screw-threaded through the nut. 80
7. In a tool of the character described, a cross-head having a cavity therein, a nut in said cavity, means for preventing the rotation of said nut, a removable abutment secured to said cross-head adjacent said cavity, spring means acting between said abutment and nut to resist movement of the nut in one direction; and a spindle passing freely through said cross-head and screw-threaded through the nut. 85
8. In a tool of the character described, a cross-head having a cavity therein, a nut in said cavity movable toward and from the work, means for preventing the rotation of said nut, a removable closure or bushing for said cavity located between the nut and the work, spring means acting between said closure or bushing and said nut to resist movement of the nut toward the work, and a spindle screw-threaded through the nut and movable endwise with it. 90
9. A tool of the character described, comprising in combination, a cross-head, a spindle adjustable endwise therethrough and capable also of endwise movement independently of said adjustment, and rods mounted for endwise adjustment on each side of said spindle. 95
10. A tool of the character described, comprising in combination, a cross-head, a spindle adjustable therethrough toward and from the work, blocks mounted in said cross-head for universal self-adjustment, and rods carried by said blocks. 100
11. A tool of the character described, comprising in combination, a cross-head, a spindle adjustable therethrough toward and from the work, blocks mounted in said cross-head for self-adjustment toward and from said spindle, and rods passing through said blocks. 105
12. A tool of the character described, comprising in combination a cross-head, a spindle adjustable therethrough toward and from the work, blocks mounted in said 110
13. A tool of the character described, comprising in combination, a cross-head, a spindle adjustable therethrough toward and from the work, and rods having a universal mounting in said cross-head. 115
14. A tool of the character described, comprising in combination, a cross-head, a spindle adjustable therethrough toward and from the work, and rods having a spring and frictional universal mounting in said cross-head. 120
15. A tool of the character described, comprising in combination, a cross-head, a spindle adjustable therethrough toward and from the work, trunnion blocks mounted in said cross-head for self-adjustment toward and from said spindle and movable also in other directions than that at right angles to the axis of the trunnion, and rods mounted in said blocks. 125
16. In a tool of the character described, a cross-head, a trunnion block in frictional contact at its ends with surfaces of said cross-head and having a cavity in its end and spring means mounted therein for co-action with a surface of the cross-head, and a rod passing through said trunnion block. 130
17. In a tool of the character described, a cross-head, a block mounted in said cross-head having a cavity in one end, a spiral spring in said cavity acting against a surface of said cross-head, and a rod supported by said block. 135
18. In a tool of the character described, a cross-head, a block mounted in said cross-head having an enlarged cavity in each end, a spiral spring loose therein acting against a surface of said cross-head, said block having a hole intermediate its ends, and a rod passing through said hole. 140
19. A tool of the character described, comprising in combination, a cross-head having a body portion and slots extending outward therefrom on each side thereof, a spindle adjustable endwise through said body portion toward and from the work, self-adjusting trunnion blocks movable within said slots toward and from said body portion, and rods passing through said trunnion blocks and secured thereto. 145
20. A tool of the character described, comprising in combination, a cross-head having a body portion and slots extending outward therefrom on each side thereof, a spindle adjustable endwise through said body portion toward and from the work, self-adjusting trunnion blocks movable within said slots toward and from said body portion, each of said trunnion blocks having 150

spring means in its ends facing the sides of said slots and having a hole intermediate said ends, pull rods passing freely through the holes in said trunnions, and a pair of 5 nuts below and above said trunnions screw threaded on said rods to effect and retain their longitudinal adjustment.

21. A tool of the character described comprising in combination, a cross-head having 10 a central body portion and slots on each side thereof having inwardly extending ledges at the top and bottom, a spindle screw threaded in said body for endwise adjustment toward and from the work, trunnion 15 blocks within said slots between said ledges and self-adjusting to and from said spindle, rods passing through said slots and trunnion blocks and adjustable with respect thereto, and means on the ends of said pull rods for coacting with the work.

22. A tool of the character described comprising in combination, a cross-head, a central spindle screw threaded for endwise adjustment through said cross-head toward 25 and from the work, rods mounted in said cross-head, means for yieldingly supporting the said spindle against endwise movement, and a removable protector cap for the upper end of said spindle.

30 23. In a tool of the character described, a removable cap for a spindle end having solid but relatively yielding material for contact with the end of the spindle.

24. A tool of the character described, 35 comprising in combination, a bed plate, means for supporting the same, upright rods secured to said plate and extending up

therefrom, a cross-head supported by said rods, and a spindle yieldingly and ad 40 istably mounted in said cross-head for coö 40 operation with work on said bed plate.

25. A tool of the character described, comprising in combination, work engaging means, rods secured thereto, a cross-head adjustable toward and from said work en- 45 gaging means, a spindle screw threaded for endwise adjustment through said cross-head and mounted for endwise movement independently of said adjustment, and spring means for yieldingly opposing said 50 movement.

26. In a tool of the character described, a cross head, a block adjustable thereon, a rod freely movable endwise therethrough, said rod being screw threaded, and a pair of nuts 55 screw-threaded on said rod one above and the other below said block.

27. In a tool of the character described, a cross head, a rod mounted for adjustment on said cross-head, and spring means asso- 60 ciated with said rod and acting frictionally against said cross-head to permit but retard said adjustment.

28. In a tool of the character described, a cross-head, a block adjustable thereon, and 65 spring means associated with said block and acting frictionally against said cross-head to permit but retard said adjustment.

In testimony whereof I affix my signature in presence of two witnesses.

TACITUS WM. GAILLARD.
